UNITED STATES PATENT OFFICE

CURTIS F. WELLINGTON, OF LEOMINSTER, MASSACHUSETTS

SHOE AND HOSIERY BENCH

Application filed February 18, 1929. Serial No. 340,709.

This invention relates to an article of furniture which is constructed in the form of a bench suitable for general use but adapted especially for use with a vanity and having 5 within it a shoe rack and a hosiery drawer.

The principal objects of the invention are to provide a piece of combination furniture for this purpose having a neat and attractive appearance when used as a bench and capable 10 of being opened easily to expose the shoe rack at an inclined position and at a comparatively high level so that the shoes may be reached conveniently; to provide a construction in which the opening of the doors 15 will swing the shoe rack upwardly in a convenient position for the removal of shoes; to provide a convenient receptacle for shoes occupying no space except that which is wasted ordinarily, and to provide an improved construction of a shoe rack and a convenient location for the hosiery drawer.

Other objects and advantages of the invention will appear hereinafter.

Reference is to be had to the accompanying 25 drawings in which

Fig. 1 is a front elevation of a bench constructed according to this invention and shown in closed condition;

Fig. 2 is an end elevation thereof;

Fig. 3 is a sectional view on the line 3—3 of Fig. 1;

Fig. 4 is an end view showing the doors opened and the top of the bench and shoe rack swung upwardly;

Fig. 5 is a front view with the parts in the same position;

Fig. 6 is a transverse sectional view on enlarged scale, showing the device opened, and

Fig. 7 is a sectional view on the line 7—7 of 40 Fig. 6.

The disposal of shoes is a matter of considerable annoyance in many homes. In spite of all the articles of furniture with which homes are usually provided there is 45 no place for shoes except on the closet floor or on racks usually intended to be hung in a closet on the inside of the door or in an extra cabinet occupying floor space. Furthermore, the ordinary benches for vanities are of such 50 a nature that they take up considerable room

and the parts underneath constitute waste space.

The idea of this invention is to utilize the space under the top of such a bench for the purpose of storing shoes and hosiery and to 55 construct the bench in such form that the shoes will be in a convenient position to be reached from the front of the bench.

It will be seen that the bench is constructed in general in an ordinary way with four 60 vertical legs 10 and a top 11, provided with suitable cushions as desired. Instead of being all open, it is closed in by a rear side 12 and two ends 13 which may be of as beautiful and ornamental wood as may be desired and 65 the front is closed by a pair of doors 14 which swing in toward the center from hinges 15 at the corner legs on vertical axes.

For the purpose of storing the shoes, the top 11 is provided, rigidly secured thereto, 70 with a frame 16, preferably of sheet metal and of rectangular form, having above the bottom a parallel shelf 17 also of sheet metal. The bottom and the shelf 17 are provided with longitudinal rails 18 or cleats over which 75 the shoes are intended to be supported with the heels in front of these rails so that the shoes will not slide back in the cabinet but will stand therein right side up and all the same distance from the front of the device 80 and maintaining their position therein on account of the square front surface of the heel resting against one of these rails.

The cover is pivoted to the rear wall 12 by 85 hinges 19 on horizontal axes so that it can be moved from horizontal position to an inclined position as shown in Figs. 4, 5 and 6. It will be obvious that this motion exposes the front side of the shoe rack 16 which is open so that the desired pair of shoes can be taken out 90 very conveniently.

The device is arranged so that the movement of the top into the inclined position will open the doors 14 this being provided for by a pair of links 20, each pivoted on a vertical 95 axis to a cleat 21 on one of the doors and pivoted, by a substantially universal joint 22, to a fixed stud 23 carried by the bottom of the frame 16 near the back of the cabinet.

It will be seen therefore that the doors 100

need have no knobs for operating them as the part of the top which projects over beyond the legs can be used for tipping the top up and automatically opening the doors to expose the 5 shoes in the lower compartment of the frame 16 and especially for allowing this frame to 10 swing outwardly through the front of the device. The parts are so proportioned that when the doors are swung through an arc of 15 90° the frame will swing out into the position shown in Fig. 6 and the cover need be raised no further.

Naturally the frame 16 is located in a compartment in the bench and the bottom of this 15 compartment is closed by a floor 24. This may be a sheet of wood or metal which slides in grooved ways 25 on the stationary ends of the device and therefore can be removed. These ways or cleats 25 are secured by screws 20 to the ends of the bench inside and the iron or thin wood floor 24 is slid in along these grooves. This constitutes a covering for the parts below which can be removed for cleaning, thus making it easy to prevent the accumulation 25 of dust inside the bench.

Below this floor or covering 24 is a drawer 26 which is of ordinary shape and has buttons 27 for moving it out and in. The sides of the drawer are provided with grooves 28 arranged longitudinally which rest on cleats or guides 29 permanently fastened in the inside of the ends of the bench. This drawer is designed to contain hosiery and the cover 24 is provided so that the same will not get up into the upper part of the device and perhaps get caught in the rods 20 or the pivots at the ends of these rods which are designed to be quite loose.

It will be seen therefore that the vanity 40 bench can be made of any desirable degree of attractiveness and can be used for the purposes for which the ordinary benches are now employed and that the shoes and hosiery are located in it most conveniently where they 45 can be taken out in a simple and convenient manner. The shoe rack and hosiery drawer take up no room not otherwise required for such a bench. The doors are not capable of swinging open of their own accord and there 50 is no danger as long as the cover is down of the doors opening to get in the way of the user of the bench or allow dust to enter the interior. The hosiery drawer is well protected against the same difficulty and the articles 55 inside the bench are always in the desired position.

Although I have illustrated and described only one form of the invention I am aware of the fact that modifications can be made 60 therein by any person skilled in the art without departing from the scope of the invention as expressed in the claims.

Therefore, I do not wish to be limited in this respect but what I do claim is:—

65 1. As an article of manufacture, a bench-

like structure having a top pivoted at one side to swing upwardly, a rack secured to the underside of the top and having strips across it near the front to constitute a shoe rack, a pair of doors pivoted to the front of the structure and rods pivotally connected with said rack and with the two doors for opening the doors when the top and rack are swung upwardly.

2. In a bench, the combination with a closed body, a top pivoted at the top of the body along one side, a rack depending from the top and located inside and having shoe racks thereon, a pair of doors pivoted on the front side of the bench, a pair of rods connecting the doors with the bottom of the rack, the inner ends of said rods being pivotally connected with the bottom of the rack at points near the rear of the bench and cleats on the doors having a vertically pivotal connection with the front ends of said rods, whereby when the top is raised the doors will be opened and the front of the rack exposed.

3. As an article of manufacture, a shoe holder having a top pivoted at one side to swing upwardly, a rack secured to the underside of the top and having strips across it near the front to constitute a shoe rack, a pair of doors pivoted to the front end edges of the structure and means connected with said rack and with the two doors for opening the doors outwardly in opposite directions when the top and rack are swung upwardly.

In testimony whereof I have hereunto affixed my signature.

CURTIS F. WELLINGTON.
